DESIGN FOR A PROTECTIVE CONTAINER
FOR NURSING BOTTLESWilliam M. Ellsworth, Brooklyn, N. Y., assignor
to Michael Friedman, Brooklyn, N. Y.

Application December 10, 1946, Serial No. 135,382

Term of patent 3½ years

(Cl. D83—8)

To all whom it may concern:

Be it known that William M. Ellsworth, a citizen of the United States of America and resident of Brooklyn, State of New York, has invented a new, original, and ornamental Design for Protective Container for Nursing Bottles, of which the following is a specification, reference being had to the accompanying drawing, forming part thereof, in which,

Fig. 1 is an elevational view of a protective container for nursing bottles embodying my new design;

Fig. 2 is a top plan view thereof;

Fig. 3 is a view similar to Fig. 1, but illustrating the three parts thereof in separated position;

Fig. 4 is an enlarged plan view as seen from the line 4—4 of Fig. 3; and

Figs. 5 and 6 are enlarged bottom plan views as viewed along the lines 5—5 and 6—6 respectively of Fig. 3.

I claim:

The ornamental design for a protective container for nursing bottles, substantially as shown.

WILLIAM M. ELLSWORTH.
